UNITED STATES PATENT OFFICE.

FREDERICK ELLSWORTH INGRAHAM, OF LITTLE FALLS, NEW YORK.

HANDLE-BAR FOR BICYCLES.

SPECIFICATION forming part of Letters Patent No. 597,001, dated January 11, 1898.

Application filed August 8, 1896. Serial No. 602,198. (No model.)

To all whom it may concern:

Be it known that I, FREDERICK ELLSWORTH INGRAHAM, a citizen of the United States, residing at Little Falls, in the county of Herkimer and State of New York, have invented 5 an Improvement in Handle-Bars for Bicycles, of which the following is a specification.

My invention relates to improvements in handle-bars for bicycles; and the object of 10 my improvement is to provide a handle-bar which may be quickly raised or lowered by the rider while in motion and without necessitating the removal of the hands from the grips of the bar. I attain this object by the 15 mechanism illustrated in the accompanying drawings, in which—

Figure 1 is an elevated view of the invention, parts being shown in section. Fig. 2 is a similar view of the handle-bar as it appears 20 in the operation of adjustment. Fig. 3 is an enlarged sectional view of the central portion of the handle-bar. Fig. 4 is an enlarged sectional view of the grip. Fig. 5 is a vertical section of the grip on line 2 2, seen from the 25 rear. Fig. 6 is a top elevation of one of the cams. Fig. 7 is a detail view of the gripping-teeth. Figs. 8 and 9 show modified forms of my invention.

Similar letters refer to similar parts throughout the different views.

A represents the head-post, which is connected in the ordinary way to the steering-head of the bicycle.

B represents a sleeve rigidly attached to 35 the head-post and is provided at one end with a reduced portion C. The edge of said portion is provided with projections or teeth D.

E represents the handle-bar, which is loosely mounted in the sleeve.

F represents a collar adapted to slide longitudinally on the handle-bar and is provided at one end with a number of projections or teeth G, adapted to engage with the teeth of the sleeve. This collar is further provided 45 with a cross-piece H, adapted to engage a longitudinal slot I on the handle-bar and prevent the collar from rotating on the bar.

J represents an annular shield provided with an inwardly-projecting portion K. This 50 shield is secured to the handle-bar by means of a set-screw L.

A spiral spring M is interposed between the

portion K of the shield J and the smooth edge of the collar F. This spring exerts a constant pressure upon the collar and tends to 55 keep the teeth of the collar and the sleeve in rigid engagement with each other. The cross-piece H is connected with one of the grips of the handle-bar by means of a chain or cord N. This grip comprises a metal tube O, having at its forward end a cam-face P, adapted to engage with a corresponding cam-face on the collar Q, said collar being rigidly secured to the handle-bar. The reduced portion of the tube is provided with a cork lining R, 60 which renders the grips pleasant to hold. The rear end of the tube is provided with a ferrule S, which is cemented or otherwise secured to the cork lining.

T represents a swivel-joint of ordinary construction and is connected at one end to the cord N above mentioned and at the other end to a piston U. This piston is provided with ribs V, adapted to engage in slots W, 65 cut in the interior portion of the tube.

X represents a screw adapted to engage with the ferrule and the piston T and serves the purpose of tightening the cord.

Y represents two guide-pulleys for the cord.

In operating the invention the grip is 80 turned by the hand to one side, causing the cam-faces to engage each other and force the grips rearwardly, imparting a similar movement to the collar F, causing the teeth on said collar to disengage with the teeth of the sleeve 85 and assume a position as indicated in Fig. 2, permitting the handle-bar to rotate in the sleeve and be adjusted to any desired angle.

In the modified form of my invention as shown in Fig. 8 the shield J extends over 90 both ends of the sleeve and is permitted to slide longitudinally on the handle-bar. The shield in this construction is provided at one

end with an inwardly-projecting portion K, adapted to engage with the smooth edge of the collar F, and at the other end with a threaded portion adapted to engage a threaded ring K'. The spiral spring M is interposed between this ring and a collar E', which is rigidly secured to the handle-bar. The shield trans- 95 mits the pressure of the spiral spring to the collar E' and causes the teeth of the collar and the sleeve to rigidly engage. The shield is further provided with a slot J', which enables

the shield to clear the head-post A while sliding in a longitudinal direction.

In the modified form of the grips as shown in Fig. 9' I provide the handle-bar with a worm-groove E², with which engages a pin O', secured to the tube or sleeve O. By turning the grip the pin engages the worm-groove and forces the sleeve rearwardly and transmits its motion to the collar F by means of the cord N disengaging the gripping-teeth. The worm-groove terminates in a recess E³, which locks the pin and holds the handle-bar in a position for adjustment without any exertion on the part of the operator. The teeth or projections of the collar and sleeve are preferably made wedge-shaped at the ends, as shown in Fig. 7, in order that they may easily slide into engagement with each other.

Having thus described my invention, what I claim as new, and desire to secure by Letters Patent, is—

In a handle-bar for bicycles the combination of the head-post carrying a sleeve B, said sleeve being provided at one end with teeth

or projections D, the bar E revolvably mounted in the sleeve, the collar F adapted to slide longitudinally on the bar, said collar being provided with teeth G, adapted to engage the teeth of the sleeve, a shield J rigidly secured to the bar and provided with an inwardly-projecting portion K, a spiral spring engaging said portion and the said collar and adapted to exert a constant pressure upon the same causing the opposing teeth of the collar and the sleeve to rigidly engage each other, a cross-piece H secured to the collar and engaging a slot I on the bar, a tube or sleeve revolvably mounted on one end of the bar and provided with a cam-face P, a cam rigidly secured to the bar and adapted to engage the said cam-face, a cord connecting the gripping-collar and the sleeve, means for guiding and adjusting said cord, substantially as described and for the purpose set forth.

FREDERICK ELLSWORTH INGRAHAM.
